UNITED STATES PATENT OFFICE.

JOHN H. BISSETT, OF DORCHESTER, MASSACHUSETTS, ASSIGNOR OF ONE-HALF TO
ALFRED H. COLBY, OF MELROSE, MASSACHUSETTS.

ADJUSTABLE WINDOW-SHADE FIXTURE.

1,087,077.

Specification of Letters Patent.

Patented Feb. 10, 1914.

Application filed March 10, 1913. Serial No. 753,163.

To all whom it may concern:

Be it known that I, JOHN H. BISSETT, a citizen of the United States, and a resident of Dorchester, county of Suffolk, and State 5 of Massachusetts, (whose post-office address is No. 13 Center Court, Dorchester, Massachusetts,) have invented an Improvement in Adjustable Window-Shade Fixtures, of which the following description, in connection with the accompanying drawings, is a 10 specification, like characters on the drawings representing like parts.

This invention relates to window shades and particularly to adjustable roller window shades, and its object is to provide an improved form of fixture for that type of shade that will possess several advantages over such fixtures as commonly constructed.

Referring to the drawing of a preferred 20 form of my invention selected for illustration and description herein: Figure 1 is a front elevation of a conventional window and its casing with my improved shade fixture and a shade secured to the casing; Fig. 2, a front edge view of one of the two pulley brackets; Fig. 3, a side elevation of the same, viewed from the right Fig. 1; Fig. 4, a development of the same as it appears 25 when cut out of a sheet of flat material; Fig. 5, a cross sectional view on the line 5-5, Fig. 3; Fig. 6, a front view of one of the two rod supporting brackets; Fig. 7, a side view of the same; Fig. 8, a development of the same, as it appears when cut from flat material; Fig. 9, a side elevation of one of the 30 roller carrying brackets; Fig. 10, a top edge view of the same; Fig. 11, a side elevation of the opposite roller carrying bracket, and Fig. 12, a top view of the same.

Referring first to Figs. 1 to 3, my improved adjustable shade and fixture comprises two pulley brackets, 2, 3, secured at opposite sides and at the top of the window casing, two guide rod supporting brackets 45 4, 5, Figs. 6-7, similarly disposed at the bottom of the window casing, guide rods 6, 7, herein rectangular, Figs. 1, 5, 10, 12, carried by said brackets; roller brackets 8-9, Figs. 1, 9 and 11, slidably mounted on said 50 rods 6-7, a roller 10, shade 11, and cords 12, 13, secured respectively to the brackets 8, 9, and carried over pulleys 14, 15, Fig. 1, and to a convenient cleat or securing member 16.

Heretofore the guide rods and brackets

therefor used in connection with adjustable shades of this type have been designed and adapted for use, first; upon the outer or front face of the window casing, or second; upon the inner edge thereof adjoining the 60 sash, but they have not been designed for use in either position as desired. This fact has resulted in great inconvenience and expense for the reason that it has compelled a dealer to keep in stock both kinds of fixtures for use as required. To avoid this inconvenience and expense, I have invented the universal fixture illustrated herein and adapted to be used at will in either of above 65 positions, and will now proceed to describe 70 the several members thereof and manner of using the same.

The pulley brackets 2, 3, Fig. 1, are formed preferably by properly folding a blank 17, see Fig. 4, of suitable material, as metal. 75 This blank having been first cut with the outline shown in Fig. 4 and a U-shaped aperture 18, the wing 19 is bent outwardly to the left, see Figs. 2, 5, if the bracket is to be a right hand bracket, that is, to be used 80 on the upper right hand corner of the casing, Fig. 1, and the wing 19 is bent or folded in the opposite direction, or to the right, if the bracket is to be a left hand bracket, as if it is to be used at the upper left hand corner. 85 It being, for instance, the intention to form a right hand bracket, Figs. 1 to 4, the blank 17 is next folded along the dotted line 20 parallel with the wing 19, Fig. 5, next at right angles thereto, again parallel with 90 the wing 19 and finally to the left, Fig. 5, in line with body of the blank. It is understood, of course, that the words "parallel" and "right angle" are used in their common and general sense and not to specify a 95 mathematically exact mechanical construction, and the same is true when they are used hereafter. The depending tongue 21 is next offset outwardly, Fig. 3, to the extent that it is desired the bracket shall be positioned 100 from the front face of the casing, if an outside bracket, and the adjacent tongue 22, Figs. 2, 3, 5, is offset outwardly at right angles thereto, see Fig. 5, to the extent that it is desired the bracket shall be positioned 105 from the inner edge of the casing, if the bracket is to be used as an inside bracket, on said inner edge of the casing, see dotted position, Fig. 1.

The wing 23, Fig. 4, is finally folded 110

down upon the upper edges of the various folded portions of the blank as described, to form a top, Fig. 3, thus completing the 5 socket to receive the upper end of one of the guide rods 6, 7. If the bracket is to be a left hand bracket, that is, to be used at the upper left hand corner of the casing the several folding operations are performed in the reverse direction as illustrated by dotted 10 lines, Fig. 5. A pulley 24 is next mounted in the bracket by means of the holes 25 and the lower edge of the bracket, if a right hand bracket, is offset somewhat, at 24^a, Figs. 2, 3, to permit the cord 13 to be received therein for a purpose to be subsequently described.

The guide rod supporting brackets 4, 5, are alike and may be constructed similarly to the brackets 2, 3, by suitably folding the 20 blank 26, see Fig. 8, provided with a tongue 27. This blank is first folded at right angles to the tongue 27, next parallel to the tongue 27, again at right angles thereto parallel with the first fold, and the wing 28 25 is then folded across the bottom edge of said folds, Fig. 6, to form a bottom, and the tongue 27 finally offset the same distance as tongues 21, 22, completing the bracket which may, of course, be used at either 30 front face as an outside bracket or the inner edge of the casing as an inside bracket.

The roller brackets 8-9, may be conveniently stamped out of the same sheet material as the brackets, or of any other suitable material. The bracket 8, is in the general form of a yoke, the two arms 29-30, of which are folded, see Fig. 10, to form a rod embracing portion adapted to slidably receive the rod 6. The nose 31 of the blank 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 tion. Owing to the tops 23, of the pulley brackets and bottoms 28 of the guide rod brackets, which act to prevent the guide rods from moving vertically in said brackets, it is unnecessary to either head over the ends of the rods 6, 7, or provide them with nuts or other fastening means as is commonly done. The roller 10 of desired type, with its shade 11, is next placed in position by first inserting the round post of the roller in the hole 33 of bracket 9, and next by dropping the rectangular post of the roller into the slot 32 of the bracket 8, the shoulder 35 of said bracket serving to prevent the post from jumping out from said slot under ordinary circumstances. The cords 12, 13, are next attached to the brackets 8, 9, in the usual manner by means of the holes 34, the cord 12 being carried over both pulleys in the brackets 2, 3, and the cord 13 over the pulley in the bracket 3 only, the former cord being carried down outside bracket 3, and the latter cord carried down in the offset position 24^a at the inside of the bracket, thus keeping the cords separate and preventing twisting thereof. The cord 13 is preferably conveniently secured to the cord 12 at a suitable point between the bracket 3 and the bracket 5 and the end thereof secured to the cleat or other member 16. The shade 11 and its roller 10 may now, by means of the cords 12, 13, conveniently be adjusted at any desired point between the upper and lower ends of the window casing.

As fixtures of this type are commonly constructed at present when the guide rods used are round and the roller brackets rotatable thereon, it is necessary to provide the roller end posts or studs with heads to prevent lateral displacement of the brackets which would thus allow the roller to drop therefrom. This difficulty is avoided in some cases by providing the round guide rods with a flange or web which prevents rotation of the roller brackets thereon while permitting them to slide vertically thereof and serves, when bent laterally to form flanges for attaching the rods to the casing by means of screws or tacks. Such rods, however, must be made especially for such use and are expensive and necessitate nailing or securing the same at frequent intervals to the casing thus unnecessarily marring the same. Even in such cases it is sometimes deemed necessary to provide the roller posts or studs with heads to prevent any lateral movement of the roller; or as a substitute for this construction the opposite roller brackets are sometimes secured by a brace and connecting rod which unites them and prevents rotation thereof about the round guide rods. Again, it has been common to mount the roller studs or posts in blocks, which in turn are constructed to

travel up and down the casing, at its inner edge, between parallel strips secured to said casing. This construction is particularly clumsy and disfiguring.

5 My improved construction, as shown and described herein, eliminates all the disadvantages referred to.

10 The rectangular guide rods may be of standard size, rods always kept in stock, and therefore less expensive than when and if made to order, and the roller brackets being formed to embrace the same, they of course, cannot be moved thereabout and they thus prevent lateral movement of the roller.

15 The roller brackets may, of course be used, like the guide rod supporting brackets and pulley brackets with the rods 6, 7, either at the face or inner edge of the casing at will.

20 One advantage of using the brackets and their coöperating rods with the curtain and its roller inside or between the opposite edges of the window casing is that such use brings the curtain nearer the sash and that

25 consequently excludes more light from the room. If the brackets are used on the inner facing of the window casing, the curtain is removed from the sash a distance equal to the distance from the sash to the inner face

30 of the casing plus the distance from said casing to the roller in its position at the outer ends of the brackets 8, 9. If the brackets are positioned upon the opposite edges of the window casing, and substan-

35 tially against the window sash, as shown in dotted lines Fig. 1, the curtain will be positioned from the sash a distance equal to the distance from the sash or, Fig. 3, from the member 21 to the rod 5 which will be positioned in the socket provided with a cover

40 23 plus the distance from the rod to the

aperture 33 of the bracket 9, thus bringing the curtain much nearer to the window sash. In either case the rods 6, 7 coöperate in the same manner with the brackets 2, 3, 4 and 5 45 not only to guide the roller when it is raised or lowered, but also to prevent any lateral swinging of the roller or curtain and also to prevent any swinging of the roller and curtain toward or from the window sash, as the 50 ordinary curtain is apt to be swung by the wind if the window is open.

In some cases, as in factories, store rooms or offices, where it is desired simply to exclude the sun, it is sufficient to place the curtain fixtures and curtain on the inner facing 55 of the window casing, as shown in Fig. 1; on the other hand, in dwellings and rooms where privacy is desired, it is desirable to have the curtain positioned as close to the 60 sash as possible and in that case the fixture described herein may be used with equal facility as described above.

Having described a preferred form of my invention which, however, may doubtless be 65 modified within the spirit thereof, I claim:

In an adjustable window shade fixture, a bracket provided with a pulley and a socket to receive the upper end of the shade roller bracket guide rod, said bracket having offset tongues in planes substantially at right angles to each other affording a means for attaching the bracket and thereby supporting the rod to the edge or to the inner face of the window casing. 75

In testimony whereof, I have signed my name to this specification, in the presence of two subscribing witnesses.

JOHN H. BISSETT.
